PIANO OR SIMILAR ARTICLE

William H. Clingman, Grand Rapids, Mich., assignor to Meridan Corporation, Chicago, Ill., a corporation of Washington

Application March 9, 1959, Serial No. 54,886

Term of patent 14 years

(Cl. D56—9)

The back of the piano is substantially plain and unornamented.

I claim:

The ornamental design for a piano or similar article, as shown and described.
